UNITED STATES PATENT OFFICE

139,592

DESIGN FOR A WHEELED TOY

Eugene M. Belknap, Toledo, Ohio

Application September 23, 1944, Serial No. 115,426

Term of patent 14 years

(Cl. D34—15)

To all whom it may concern:

Be it known that I, Eugene M. Belknap, a citizen of the United States, and resident of Toledo, in the county of Lucas and State of Ohio, have invented a new, original, and ornamental Design for a Wheeled Toy, of which the following is a specification, reference being had to the accompanying drawing, forming a part thereof.

In the drawing, Fig. 1 is a perspective view of a wheeled toy showing my new design; Fig. 2 is a side view thereof, and Fig. 3 is a reduced perspective view similar to Fig. 1 with the top member of the toy raised slightly above the body of the toy to disclose the configuration of the latter.

I claim:

The ornamental design for a wheeled toy, substantially as shown.

EUGENE M. BELKNAP.
